Application March 17, 1950, Serial No. 150,301

20 Claims. (Cl. 1-6)

1

This invention relates to apparatus for handling tacks and particularly to a novel and improved mechanism for feeding and separating tacks. Although the herein illustrated embodiment of the invention is shown as applied to a lasting machine of the so-called hand method type, it will be understood, of course, that the tack-feeding and separating mechanism of this invention is of broader utility and, therefore, not limited to use either in a lasting machine or in a machine of the exact mechanical construction shown.

A well-known type of tack-handling apparatus used, for example, for delivering tacks to the tack nozzle of a lasting machine includes an inclined raceway provided with a tack-feeding groove along which a line of tacks is fed by gravity to the lower end thereof and a reciprocating separator for separating the lowermost tack from the line and delivering it to a discharge passage through which the tack falls into the tack nozzle of the machine. Usually, this separator comprises a relatively thin plate having an angularly disposed slot for engaging the lowermost tack in the raceway, just beneath its head, and for transferring the tack to a discharge passage during reciprocation of the separator, in the manner illustrated, for example, in United States Letters Patent No. 1,014,940, issued on January 16, 1912 in the name of W. A. Bond. While separating mechanisms of this type have proved to be generally satisfactory in use, the relatively thin separator blade is susceptible to considerable wear and, inasmuch as the tack being separated is supported only in a location just beneath its head, there is some tendency for it to be tipped, or tilted, out of proper position to drop freely through the discharge passage. Also, it is necessary with a tack separator of this kind to provide, in addition to the separator blade, a so-called gate member for holding the line of tacks in the raceway groove, during each separating operation, together with a member having a slot which cooperates with the separator slot for effecting the transfer of the separated tack to the discharge passage.

It is an object of this invention to provide novel and improved tack-separating mechanism which is not only much less susceptible to wear and more positive in its action but is also very dependable in operation and so constructed as to prevent the separated tack from being displaced from a proper position to drop freely through the discharge passage. To this end, and in accordance with a feature of the invention, there is provided a separator member which is moved in such a way as to bring a tack-receiving recess therein, alternately, into alignment with a tack-feeding groove or a discharge passage, formed in the lower end of the raceway, the separator also car-

rying means for positively ejecting a tack from the recess each time the separator is moved to bring the recess into alignment with the discharge passage. More particularly, the separator comprises a member arranged to be reciprocated along the vertically disposed end face of an inclined raceway and having a slot cut through its upper portion to provide a tack-receiving recess of a depth at least as great as the length of the stem of the longest tack to be handled, while the tack ejector is formed by a member that is slidably mounted in the slot and which extends substantially from the top of the separator to the bottom of the slot. This ejector member is moved toward and away from the end face of the raceway in such time relation to the reciprocating movements of the separator that the member is withdrawn from the end face of the raceway to permit the endmost tack in the tack-feeding groove to enter the slot, when the slot is in alignment with the tack-feeding groove, and is projected toward the end face of the raceway to eject the tack from the slot and into the discharge passage, when the slot is in alignment with the discharge passage. With this arrangement, the endmost tack in the tack-feeding groove of the raceway feeds by gravity into the tack-receiving recess of the separator, and, during transfer to the discharge passage, this tack is confined throughout the entire length of its stem by the sides of the tack-receiving slot, the withdrawn ejector member and the end face of the raceway, so that it cannot be displaced from a proper position to drop freely through the discharge passage when positively moved thereinto by the ejector member.

The raceway is inclined from the horizontal at an angle sufficient to cause the tacks to slide along by gravity and to move out of the raceway and into the separator, and, in accordance with another feature of the invention, the separator is provided with an upper surface which is inclined in a direction opposite to the raceway. Thus, when a tack moves out of the raceway and into the separator, its head will rest on this inclined surface so as to cause the stem of the tack to be swung out of the tack-feeding groove, away from the end face of the raceway, and into the tack-receiving recess of the separator. Accordingly, when the separator is moved to transfer this tack to the discharge passage, there will be no danger of the stem of the tack catching on the end of the raceway, or in the tack-feeding groove, in such a way as to interfere with such movement of the separator. In order to facilitate the action of the separator and, more particularly, to cause the stem of a tack received by the separator to swing away from the raceway in the manner explained above, it is important that the tacks in the raceway groove be

maintained in a predetermined relative position, i. e., "shingled" with the head of each succeeding tack superposed on the head of the preceding tack, so that the stems of these tacks are free to assume a nearly vertical position. With this end in view and in accordance with another feature of the invention, the raceway of the herein illustrated machine is provided with means for causing the tacks to assume this proper "shingled" position as they feed along by gravity. More particularly, the inclined raceway is provided with a tack-feeding groove and adjacent flat surfaces along which the heads of the tacks rest with their stems suspended in the tack-feeding groove and, adjacent to the upper end of the raceway, these flat surfaces are interrupted by portions of considerably less inclination than that of the raceway. With this arrangement, as each succeeding tack drops into these interrupted portions of the raceway surfaces, herein illustrated as being formed by notches having bottom surfaces of considerably less inclination than the raceway, the leading edge of its head will be superposed on the trailing edge of the preceding tack and this relationship will be maintained as the line of tacks moves down the raceway. Preferably, the clearance space between the upper surface of the raceway and a cover member, above the aforementioned notches, is such as to prevent "shingling" of the tacks before they reach these notches.

The above and other objects and features of this invention will appear from the following detailed description of the preferred embodiment thereof, illustrated in the accompanying drawings, and will be pointed out in the claims.

In the drawings,

Fig. 1 is a view in perspective of a portion of a lasting machine provided with the improved tack-handling apparatus of this invention;

Fig. 2 is a plan view of a tack-separating mechanism which forms a part of the improved tack-handling apparatus;

Fig. 3 is a view in side elevation of the tack-separating mechanism;

Figs. 4 and 5 are views in side elevation of a portion of the tack-separating mechanism shown in Fig. 3 at a somewhat larger scale and viewed at a slightly different angle, with some parts broken away and others shown in section;

Fig. 6 is a plan view of a portion of the tack-separating mechanism shown in Fig. 3 at a larger scale;

Figs. 7 and 8 are perspective views of the tack-separating mechanism, shown in different operating positions and with parts shown broken away;

Fig. 9 is a view in vertical section of a portion of the tack-feeding mechanism; and

Fig. 10 is a view in section and at an enlarged scale of a part of the tack raceway shown in Fig. 9.

Referring to these drawings, and particularly to Fig. 1, the improved tack-handling apparatus of this invention is therein illustrated as applied to a so-called "hand method" lasting machine of the type illustrated in United States Letters Patent No. 584,744, issued on June 15, 1897 in the names of S. W. Ladd and R. F. McFeely, as modified in some respects in the manner shown in United States Letters Patent No. 999,233, issued August 1, 1911 in the names of S. W. Ladd and E. A. Stiggins. In common with lasting machines of this type, the herein illustrated machine is provided with an overlaying member in the form

of a tack nozzle 20, which is carried by a reciprocating slide 22, a driver 24 for driving tacks through the nozzle, a tack raceway 26, carried by a supporting rod 28, a tack pot 30 and an edge gage 32. Except as will be noted below, these various elements are constructed like, and operate in the same manner as, the corresponding elements of the machines disclosed in the aforementioned patents to which reference may be made for details not set forth herein.

The improved tack-handling apparatus includes a novel tack-separating mechanism which is illustrated in detail in Figs. 2-8 of the drawings. Referring to Figs. 1 and 3, the lower end of the raceway-supporting rod 28 is secured, in the usual manner, to the machine frame 34 by means of a screw 36, while the raceway is fixed to the rod 28 by means of a screw 38, see Figs. 4 and 5. The raceway 26, which, except as noted below, is of conventional construction, is provided with a pair of tack-guiding grooves, or slots, 40, 42, Figs. 3, 7 and 8, and is connected to the tack pot 30 in the usual manner as shown in Fig. 9. The tack-feeding grooves 40, 42 extend out through a vertical surface 44, formed on the lower end of the raceway, and midway between these grooves this vertical surface is cut away to provide a discharge passage 46, Figs. 6, 7 and 8. Tacks are selectively separated from one or the other of the two grooves 40, 42 and delivered to the discharge passage 46 by means of a reciprocating separator, indicated generally by the reference character 50, and in a manner about to be explained.

The tack separator 50 is slidably mounted between the vertical surface 44 on the end of the raceway and the front face 52 of a bracket member 54 that is secured to a supporting plate 56 by means of screws 58, Figs. 2, 4 and 5. The bracket member 54 is recessed at 60 to receive a flange portion 62, formed on the lower part of the separator, Figs. 4 and 5, and the recess 60 opens into a groove 64. A projection 66, formed integrally with the flange 62, extends into the groove 64 so that reciprocating movements of the separator, in either direction, will be limited by engagement of this projection with one of the sides of the groove, Figs. 6, 7 and 8. The separator 50 is traversed by a vertical slot 70 of slightly greater depth than the length of the longest tack to be handled, see Figs. 4-8, and this slot is intersected by means of a groove 72, formed on the side of the separator remote from the end of the raceway and terminating in a horizontal slot 74 that is cut through the separator, Figs. 6 and 7. Pivotally mounted on the separator, by means of a headed pin 76, is an arm 78 and formed integrally with one end of this arm is a rectangular shaped block 80 which is located in the vertical slot 70, Figs. 6, 7 and 8. A leaf spring 82, mounted on a laterally extending portion 84 of the separator, projects through the horizontal slot 74 and holds the arm 78 and block 80 in the position shown in Figs. 6 and 7, when the slot 70 is in line with either one of the two raceway grooves 40, 42. However, when the separator is shifted to a position in which the slot 70 is brought into alignment with the discharge passage 46, the arm 78 and block 80 are moved to the position shown in Fig. 8 by means of a cam member 86, formed on the arm 78, and a leaf spring 88 having an offset end 90 and mounted on a bracket 54 by means of a screw 92. As will be apparent, when the separator 50 is moved to a position where the slot 70 is in alignment with one or the other of the

two raceway grooves, the lowermost tack in this raceway groove will pass into the slot 70, see Figs. 4 and 7. Now, when the separator is moved to a position where the slot 70 is in line with the discharge opening 46, this tack will be ejected, by the block 80 on the arm 78, into the discharge opening 46, see Figs. 2 and 8.

For reciprocating the separator 50 in such a way that it may be caused to separate tacks, selectively, from either one of the two raceway grooves 40, 42 and deliver them to the discharge opening 46, the following mechanism is provided. The supporting plate 56 is secured, by means of screws 100 and dowel pins 102, to an offset boss 104 that is formed integrally with the lower end of the raceway-supporting rod 28, Figs. 3 and 6. The overlaying member, or nozzle, 20, of the lasting machine is secured to the lower end of the reciprocating slide 22 by means of screws 106 and interposed between this slide and the nozzle is a plate 108, Fig. 2. Adjustably secured to the plate 108, by means of a screw 110, is a second plate 112 which lies beneath the supporting plate 56, Figs. 2 and 3. The plate 112 is formed with a boss 114 through which a bore 116 extends. Journalized in this bore is a trunnion shaft 118, Fig. 3, that is formed integrally with an arm 120, provided with a rectangular groove 122, Figs. 2 and 3. Mounted on a stud 124, secured to the lower end of the raceway-supporting rod 28, is a bell-crank lever 126, Figs. 2, 4 and 6, and pivoted on one arm 128 of this bell-crank lever, by means of a stud 127 and nut 129, is a block 130 which is arranged to slide along the groove 122 in the arm 120.

Fixed to the lower end of the stud 118 is a shift cam 132, Fig. 3, that is provided with an arcuate surface 134, Fig. 2, and bearing against this arcuate surface is a plunger 136 which is mounted in a lever 138. This plunger is slidably received in a sleeve 140 that is fixed on a boss 142, formed on the lever 138, and carries a threaded stem 144, Fig. 3. This stem passes through an opening in a second boss 146, formed on the lever 138. A coil spring 148, surrounding the stem 144, bears at one end on the plunger 136 and at its other end on the boss 146. Movement of the plunger 136 by the spring 148 is limited by a pair of lock-nuts 150 which are threaded on the stem 144 beyond the boss 146. Mounted on the plate 112 are a pair of stop studs 152, 154 and, with the lever 138 in the position shown in Fig. 2, the spring-pressed plunger 136 swings the arm 120 over against the stud 152. The lever 138 is connected, by means of a link 156, to an arm 158. This arm has a hub portion 160 that is journaled in a boss 162 formed integrally with an arm 164 that extends from the machine frame 20. Carried by the hub portion 160 is a shift arm 166. When this shift arm is moved in the direction of the arrow, Fig. 2, the plunger 136 will be shifted to the other end of the arcuate surface 134, thus causing the arm 120 to be swung over and into engagement with the stop stud 154, see dotted line position in Fig. 2. For limiting movement of the shift arm, the lever 138 is formed with a laterally extending ear 165, the rounded end of which is received in slot 167 cut in a stop member 169, Figs. 2 and 3.

During the operation of the lasting machine, the plate 112 and the arm 120 carried thereby are moved forwardly and rearwardly (downwardly and upwardly as viewed in Fig. 2) by the reciprocating slide 22. Inasmuch as the axis of the groove 122 in the arm 120 is at an angle to the direction of movement of these parts, in-

dicated by the arrow on the slide 22 in Fig. 2, when the arm 120 is in engagement with either one of the two studs 152, 154, the lever 126 will be oscillated once for each reciprocation of the slide 22. When the plate 122 and arm 120 move forwardly and away from the plunger 136, the arm 120 is held in position in the following manner. Pivotedly mounted on a forwardly extending portion of the plate 122 is an arm 170 that is provided with a tooth 172. A coil spring 174, stretched between one end of this arm and a pin 176, mounted in the plate 112, tends to swing the arm 170 in a clockwise direction and to the extent permitted by a stop pin 178 that is carried by the supporting plate 56. The forward end of the arm 120 is provided with a pair of recesses 180, 182. The recess 180 is directly in line with the tooth 172 on the arm 170 when the arm 120 is held against the stud 152, while the recess 182 is in line with the tooth 172 when the arm 120 is held against the stud 154. As soon as the plate 112 begins its forward movement, inasmuch as the stop pin 178 is stationary, the arm 170 will be swung toward the arm 120 by spring 174, so that the tooth 172 will engage one or the other of the recesses 180, 182.

The lever 126 is provided with a second arm 190, Figs. 2 and 6, and rotatably mounted on the stud 124 are a pair of arms 192, 194. These two arms are connected together by a coil spring 196 which holds the ends of these two arms in engagement with the end of the arm 190 of the lever 123 and a block 198 that is rotatably mounted on a link 200. This link, in turn, is connected to the rearwardly extending portion 84 of the separator 50 by means of a pin 201.

A complete cycle of operation of the tack-separating mechanism will now be described as it would occur with the parts in the solid line positions shown in Fig. 2. When the arm 120 is swung over into engagement with the stud 152, as shown in Fig. 2, the separator 50 will be so moved as to separate the lowermost tack from the raceway groove 42 and deliver it to the discharge opening 46, each time the slide 22 is reciprocated. Referring particularly to Figs. 2, 7 and 8, at the beginning of an operating cycle the slide 22 is withdrawn, the separator 50 is so positioned that the slot 70 therein is in line with the discharge passage 46 and the arm 78 is moved to the position shown in Fig. 8 by the spring 88. During the forward movement of the slide 22, the arm 120 is locked in position by the tooth 172 on the arm 170, the separator 50 is shifted to the position shown in Fig. 7, with the slot 70 in line with the raceway groove 42, and the arm 78 is retracted by the spring 82, as the cam member 86 moves away from the offset end 90 of the spring 88. The lowermost tack T in the raceway groove 42, urged downwardly by the tacks that are behind it, now slides out of the raceway and into the slot 70 of the separator until its stem engages the block 80 on the end of the arm 78, see Figs. 4 and 7. As the slide 22 moves rearwardly, the separator 50 is returned to the position shown in Figs. 2 and 8 and just as this position is reached, the offset end 90 on the spring 88 engages the cam portion 86 and swings the arm 78 toward the separator, thus causing the block 80 on the end of the arm 78 to eject the tack positively from the slot 70 in the separator and into the discharge opening 46. Tacks thus delivered to the discharge opening fall downwardly therethrough and into the nozzle 20 in the usual manner.

The operating cycle which has just been de-

scribed is repeated during each reciprocation of the slide 22, and nozzle 20 carried thereby, so long as the lasting machine is in operation. When it is desired to separate tacks from the other raceway groove 43, which will usually be of a different size and/or length than those in the groove 42, the operator merely swings the shift arm 166 in the direction of the arrow, Fig. 2. Now, just before the slide 22 completes its rearward movement, the locking arm 170 will release the arm 120 which will immediately be swung over against the stud 154 by the action of the plunger 139 on the shift cam 132. On the next forward movement of the slide 22, the separator 50 will move over to a position to receive a tack from the raceway groove 43 and this tack will be delivered to the discharge passage 46, when the slide 22 is returned, in the same manner as before. Hence, regardless of when the shift arm 166 is moved by the operator, the position of the arm 120 will not be changed until the end of a tack-separating cycle when the slide 22 is returned to the position shown in Fig. 2 and the arm 120 released. Inasmuch as at that time in the operating cycle the axes of the studs 118 and 127 are substantially in alinement, see Figs. 2 and 3, such movement of the arm 120 will not disturb the position of the separator.

Referring now to Figs. 4 and 7, the space in front of the block 80 in the slot 78 of the separator 50 is somewhat deeper than the thickness of the stem of the longest tack to be handled and the width of this slot is of equal magnitude. In order to insure that the stem of each tack will move out of its raceway groove and into this space in the slot 78, the upper surface of the separator 204 is inclined as shown more clearly in Figs. 4 and 5. As the lowermost tack in a raceway groove is pushed into the separator slot, by the action of gravity and the line of tacks behind it, the forward edge of its head will rest on this inclined surface. Therefore the stem of the tack will swing toward the block 80 and away from the surface 44 on the end of the raceway, see Fig. 4, thus avoiding any tendency for the stem of the tack to become jammed between the separator and the raceway. As has already been pointed out, the depth of the slot 78 is just slightly greater than the length of the longest tack to be handled, while the space in front of the block 80 is just a little wider and deeper than the stem of the tack. Hence, when the separator moves to deliver a separated tack to the discharge opening, i. e., from the position shown in Fig. 7 to that shown in Fig. 8, the stem of the tack is completely confined by the walls of the slot 78, the block 80 and the vertical surface 44 on the end of the raceway. Therefore, with this separator construction, it is impossible for the tack to be displaced, or tilted out of a proper position for falling freely down through the passage 46 and into the nozzle 20.

In spite of whatever precautions may be taken, it will frequently happen that some of the tacks that are delivered to the raceway grooves 40, 42 are misshapen or bent, as indicated by the tack T₂ in Fig. 5, so that jamming occurs. Damaging of the tack separator and/or its operating mechanism under the above circumstances is prevented in the following manner. Actual movement of the separator by the lever 126 is effected through the arm 190 of this lever and the freely rotatable arms 192, 194, which are connected together by the coil spring 196. When

movement of the separator is prevented, as, for example, by the jamming of a bent tack, as illustrated in Fig. 5, the spring 196 will yield and permit full oscillation of the lever 126 without movement of the separator in the manner illustrated in Fig. 6. In order to facilitate removal of a jammed tack, the following construction is provided. The raceway 26 is provided with a cover 210 that is removably secured in place on the raceway by means of a thumb nut 212, Fig. 1. At its lower end this cover is cut away at 214, Figs. 4 and 5. A block 216, provided with a shoulder 218 and having a lower surface 220 is secured to the end of a curved leaf spring 222. This spring is slotted in two places at 224 and 226 and is held in place on the cover 210 by means of a headed stud 228, which passes through the slot 224, and a screw 230 which passes through the slot 226. When the block 216 is in the position shown in Fig. 4, the lower surface 220 thereof forms a continuation of the underneath side of the cover 210. However, access to the lower end of the raceway grooves 40, 42 and separator 50 may be quickly and easily obtained, without removal of the cover 210, by shifting the block 216 to the position shown in Fig. 5.

In order to assure that the tacks will descend along the raceway grooves 40, 42 in proper position, i. e., "shingled" in the right direction, to enter the slot 78 of the separator 50 in the manner shown in Fig. 4, the following arrangement is provided. In Fig. 9 one-half of a double tack pot and raceway construction, similar to that shown in Figs. 63 and 65 of United States Letters Patent No. 584,744, referred to above, is illustrated. Each of the raceway grooves 40, 42 is extended into the tack pot by means of a pair of spaced plates 300, 302 and, where these two pairs of plates emerge from the tack pot 30, they are covered by a removable block 304 in the manner disclosed in United States Letters Patent No. 1,014,940, mentioned above. The pair of spaced plates 300, 302 which appear in Fig. 9 constitute an extension of the raceway groove 42, while a similar pair of plates, which do not appear in Fig. 9, are arranged to constitute an extension of the raceway groove 40.

Referring to Fig. 10, which is a view at a greatly enlarged scale of adjoining portions of the plate 302, block 304 and raceway 26, the upper flat surface of each of the plates 300, 302, along which the heads of the tacks ride, is interrupted by a notch 310 having a bottom 312 that is disposed at an angle to, and more nearly horizontal than, the upper surface of each plate. When tacks are received between the two plates 300, 302, as a result of the action of the tack pot mechanism, these tacks may assume various positions in the manner indicated at the upper left-hand portion of Fig. 10, above the notch 310. However, as each tack reaches and drops into the notch 310, it will be swung, by the action of gravity on its stem, into the position shown in Fig. 10. Now, as the next succeeding tack comes along, the leading edge of its head will be located somewhat above the trailing edge of the tack that is in the notches 310 in the plates 300, 302. Hence, as the line of tacks travel along and out of the notch 310, their heads will necessarily be "shingled" in the right direction, as shown in the lower portion of Fig. 10, beyond the notches 310. In order to prevent "shingling" of the tacks before they drop into the notches 310, which might occur improperly with the leading edge of a tack beneath the trailing

edge of the preceding tack, the clearance space, between the underside 306 of the block 304 and the upper surfaces of the plates 300, 302 above the notches, is preferably limited to a height that is less than twice the thickness of the head of a tack, see Fig. 10. Thus, the tacks are constrained to travel down the raceway with their heads in edge-to-edge relation until they reach the notches 310.

Having described the invention, what is claimed as new and desired to secure by Letters Patent of the United States is:

1. A tack-separating mechanism having, in combination, a raceway provided with a tack-feeding groove extending through an end face thereof and a discharge passage formed in said end face adjacent to the tack-feeding groove, a separator having a tack-receiving recess, means for reciprocating the separator so as to bring said recess into alinement, alternately, with the tack-feeding groove or the discharge passage, a member carried by the separator for positively ejecting a tack from the tack-receiving recess and into the discharge passage, each time the separator is moved to bring the recess into alinement with the discharge passage, and means for actuating said member.

2. A tack-separating mechanism having, in combination, a raceway provided with a tack-feeding groove extending through an end face thereof and a discharge passage formed in said end face adjacent to the tack-feeding groove, a separator arranged to engage the end face of the raceway and having a tack-receiving recess, mechanism for reciprocating the separator to bring said recess into alinement, alternately, with the tack-feeding groove or the discharge passage, a member carried by the separator for positively ejecting a tack from the tack-receiving recess and into the discharge passage, each time the separator is moved to bring the recess into alinement with the discharge passage, and means for actuating said member.

3. A tack-separating mechanism having, in combination, a raceway provided with a tack-feeding groove extending through an end face thereof and a discharge passage formed in said end face adjacent to the tack-feeding groove, a separator arranged to slide along the end face of the raceway and having a slot cut through its upper portion to provide a tack-receiving recess of a depth at least as great as the length of the stem of the longest tack to be handled, mechanism for reciprocating the separator to bring said slot into alinement, alternately, with the tack-feeding groove or the discharge passage, a member mounted in said slot for positively ejecting a tack therefrom and into the discharge passage, each time the separator is moved to bring the slot into alinement with the discharge passage, and means for actuating said member.

4. A tack-separating mechanism having, in combination, a raceway provided with a tack-feeding groove extending through an end face thereof and a discharge passage formed in said end face adjacent to the tack-feeding groove, a separator comprising a member arranged to slide along the end face of the raceway and having a slot cut through its upper portion to provide a tack-receiving recess of a depth at least as great as the length of the stem of the longest tack to be handled, mechanism for reciprocating said separator to bring the slot into alinement, alternately, with the tack-feeding groove and discharge passage, a member slidably mounted in the

slot in the separator and extending substantially from the top of the separator to the bottom of said slot, for positively ejecting a tack therefrom and into the discharge passage, each time the separator is moved to bring the slot into alinement with the discharge passage, and means for actuating said member.

5. A tack-separating mechanism having, in combination, a raceway provided with a tack-feeding groove extending through an end face thereof and a discharge passage formed in said end face adjacent to the tack-feeding groove, a separator comprising a member arranged to slide along the end face of the raceway and having a slot cut through its upper portion to provide a tack-receiving recess of a depth at least as great as the length of the stem of the longest tack to be handled, mechanism for reciprocating the separator to bring said slot into alinement, alternately, with the tack-feeding groove or the discharge passage, a member slidably mounted in the slot in the separator and extending substantially from the top of the separator to the bottom of the slot, and means for moving said member in the slot toward and away from the end face of the raceway, in such time relation to the reciprocation of the separator that the member is withdrawn from the end face of the raceway to permit the endmost tack in the tack-feeding groove to enter the slot, when the slot is in alinement with the groove, and is projected toward the end face of the raceway to eject the tack from the slot and into the discharge passage, when the slot is in alinement with the discharge passage.

6. A tack-separating mechanism having, in combination, an inclined raceway provided with a tack-feeding groove extending through the lower end face thereof and a discharge passage formed in said end face adjacent to the tack-feeding groove, a separator arranged to slide along the end face of the raceway and having a tack-receiving recess, said separator also having an upper surface that is inclined in a direction opposite to said raceway for engaging the head of a tack received from the tack-feeding groove and causing the stem of the tack to swing out of said groove and away from the end face of the raceway, mechanism for reciprocating the separator to bring the said recess into alinement, alternately, with the tack-feeding groove, to receive a tack therefrom, or with the discharge passage, for delivery of a tack thereto, a member carried by the separator for positively ejecting a tack from the tack-receiving recess and into the discharge passage, each time the separator is moved to bring the recess into alinement with the discharge passage, and means for actuating said member.

7. A tack-separating mechanism having, in combination, an inclined raceway provided with a tack-feeding groove extending through the lower end face thereof and a discharge passage formed in said end face adjacent to the tack-feeding groove, a separator comprising a member arranged to slide along the end face of the raceway and having a slot cut through its upper portion to provide a tack-receiving recess of a depth at least equal to the length of the stem of the longest tack to be handled, said member also having an upper surface that is inclined in a direction opposite to the raceway for engaging the head of a tack received from the tack-feeding groove and causing the stem of the tack to swing out of said groove and away from the end face of the raceway, mechanism for reciprocating the separator to bring the tack-receiving recess into alinement,

11

alternately, with the tack-feeding groove, to receive a tack therefrom, or with the discharge passage, for delivery of the tack thereto, a member slidably mounted in the slot in the separator and extending substantially from the top of the separator to the bottom of said slot for positively ejecting a tack therefrom, each time the separator is moved to bring the slot into alignment with the discharge passage, and means for actuating said member.

8. A tack-separating mechanism having, in combination, an inclined raceway provided with a tack-feeding groove extending through the lower end face thereof and a discharge passage formed in said end face adjacent to the tack-feeding groove, a separator comprising a member arranged to slide along the end face of the raceway and having a slot cut through its upper portion to provide a tack-receiving recess of a depth equal to the length of the stem of the longest tack to be handled, said member also having an upper surface that is inclined in a direction opposite to the raceway for engaging the head of a tack received from the tack-feeding groove and causing the stem of the tack to swing out of said groove and away from the end face of the raceway, mechanism for reciprocating said separator to bring the tack-receiving recess into alignment, alternately, with the tack-feeding groove, to receive a tack therefrom, or with the discharge passage, for delivery of the tack thereto, a member slidably mounted in the slot in the separator and extending substantially from the top of the separator to the bottom of the slot, and means for moving said last-named member in the slot, toward and away from the end face of the raceway, in such time relation to the reciprocation of the separator that said member is withdrawn from the end of the raceway to permit the end-most tack in the tack-feeding groove to enter the slot, when the slot is in alignment with the groove, and is projected toward the end face of the raceway to eject the tack from the slot and into the discharge passage, when the slot is in alignment with the discharge passage.

9. In a tack-separating mechanism, an inclined raceway provided with a tack-feeding groove and adjacent flat surfaces for engaging the heads of tacks in said groove, and a separator arranged to reciprocate along the lower end face of said raceway provided with a tack-receiving recess, said raceway being inclined from the horizontal at an angle sufficient to cause tacks to slide by gravity with their heads on said flat surfaces and their stems suspended in said groove, and the flat raceway surfaces being interrupted by portions of considerably less inclination than that of the raceway so as to cause the leading edge of the head of each succeeding tack to be superposed on the trailing edge of the head of the preceding tack, as a line of tacks descends along the raceway.

10. In a tack-separating mechanism, an inclined raceway provided with a tack-feeding groove and adjacent flat surfaces for engaging the heads of tacks in said groove, and a separator arranged to reciprocate along the lower end face of said raceway provided with a tack-receiving recess and having an upper surface inclined in the opposite direction to said raceway, said raceway being inclined from the horizontal at an angle sufficient to cause tacks to slide by gravity with their heads on said flat surfaces and their stems suspended in said groove, and the flat raceway surfaces being interrupted by portions of con-

12

siderably less inclination than that of the raceway so as to cause the leading edge of the head of each succeeding tack to be superposed on the trailing edge of the head of the preceding tack, as a line of tacks descends along the raceway.

11. In a tack-separating mechanism, an inclined raceway provided with a tack-feeding groove and adjacent flat surfaces for engaging the heads of tacks in said groove, and a separator arranged to reciprocate along the lower end face of said raceway provided with a tack-receiving recess, said raceway being inclined from the horizontal at an angle sufficient to cause tacks to slide by gravity with their heads on said flat surfaces and their stems suspended in said groove, and the flat raceway surfaces, adjacent to the upper end of the raceway, being interrupted by portions of considerably less inclination than that of the raceway so as to cause the leading edge of the head of each succeeding tack to be superposed on the trailing edge of the head of the preceding tack, as a line of tacks descends along the raceway.

12. In a tack-separating mechanism, an inclined raceway provided with a tack-feeding groove and adjacent flat surfaces for engaging the heads of tacks in said groove, and a separator arranged to reciprocate along the lower end face of said raceway provided with a tack-receiving recess and having an upper surface inclined in the opposite direction to said raceway, said raceway being inclined from the horizontal at an angle sufficient to cause tacks to slide by gravity with their heads on said flat surfaces and their stems suspended in said groove, and the flat raceway surfaces, adjacent to the upper end of the raceway, being interrupted by portions of considerably less inclination than that of the raceway so as to cause the leading edge of the head of each successive tack to be superposed on the trailing edge of the head of the preceding tack, as a line of tacks descends along the raceway.

13. In a tack-separating mechanism, an inclined raceway provided with a tack-feeding groove and adjacent flat surfaces for engaging the heads of tacks in said groove, and a separator arranged to reciprocate along the lower end face of the raceway provided with a tack-receiving recess, said raceway being inclined from the horizontal at an angle sufficient to cause tacks to slide by gravity with their heads on said flat surfaces and their stems suspended in said groove, and said flat raceway surfaces each being interrupted by an angular notch having a bottom surface of considerably less inclination than that of the raceway so as to cause the leading edge of the head of each succeeding tack to be superposed on the trailing edge of the head of the preceding tack, as a line of tacks descends along the raceway.

14. In a tack-separating mechanism, an inclined raceway provided with a tack-feeding groove and adjacent flat surfaces for engaging the heads of tacks in said groove, and a separator arranged to reciprocate along the lower end face of said raceway provided with a tack-receiving recess and having an upper surface inclined in the opposite direction to said raceway, said raceway being inclined from the horizontal at an angle sufficient to cause tacks to slide by gravity with their heads on said flat surfaces and their stems suspended in said groove, and the flat raceway surfaces each being interrupted by an angular notch having a bottom surface of considerably less inclination than that of the raceway so as to

cause the leading edge of the head of each succeeding tack to be superposed on the trailing edge of the head of the preceding tack, as a line of tacks descends along the raceway.

15. In a tack-separating mechanism, an inclined raceway provided with a tack-feeding groove and adjacent flat surfaces for engaging the heads of tacks in said groove, and a separator arranged to reciprocate along the lower end face of said raceway, said raceway being inclined from the horizontal at an angle sufficient to cause tacks to slide by gravity with their heads on said flat surfaces and their stems suspended in said groove, and the flat raceway surfaces, adjacent to the upper end of the raceway, each being interrupted by an angular notch having a bottom surface of considerably less inclination than that of the raceway so as to cause the leading edge of the head of each succeeding tack to be superposed on the trailing edge of the head of the preceding tack, as a line of tacks descends along the raceway.

16. In a tack-separating mechanism, an inclined raceway provided with a tack-feeding groove and adjacent flat surfaces for engaging the heads of tacks in said groove, and a separator arranged to reciprocate along the lower end face of said raceway provided with a tack-receiving recess and having an upper surface inclined in the opposite direction to said raceway, said raceway being inclined from the horizontal at an angle sufficient to cause tacks to slide by gravity with their heads on said flat surfaces and their stems suspended in said groove, and the flat raceway surfaces, adjacent to the upper end of the raceway, each being interrupted by an angular notch having a bottom surface of considerably less inclination than that of the raceway so as to cause the leading edge of the head of each succeeding tack to be superposed on the trailing edge of the head of the preceding tack, as a line of tacks descends along the raceway.

17. In a tack-separating mechanism, an inclined raceway provided with a tack-feeding groove and adjacent flat surfaces for engaging the heads of tacks in said groove, a separator arranged to reciprocate along the lower end face of said raceway provided with a tack-receiving recess, said raceway being inclined from the horizontal at an angle sufficient to cause tacks to slide by gravity with their heads on said flat surfaces and their stems suspended in said groove and the flat raceway surfaces being interrupted by portions of considerably less inclination than that of the raceway so as to cause the leading edge of the head of each succeeding tack to be superposed on the trailing edge of the head of the preceding tack, as a line of tacks descends along the raceway, and means for constraining said tacks to descend along the raceway with their heads in edge-to-edge relation until they reach said interrupted portions of the flat raceway surfaces.

18. In a tack-separating mechanism, an inclined raceway provided with a tack-feeding groove and adjacent flat surfaces for engaging the heads of tacks in said groove, a separator arranged to reciprocate along the lower end face of said raceway provided with a tack-receiving recess and having an upper surface inclined in the opposite direction to said raceway, said raceway being inclined from the horizontal at an angle sufficient to cause tacks to slide by gravity

with their heads on said flat surfaces and their stems suspended in said groove and the flat raceway surfaces, adjacent to the upper end of the raceway, being interrupted by portions of considerably less inclination than that of the raceway so as to cause the leading edge of the head of each successive tack to be superposed on the trailing edge of the head of the preceding tack, as a line of tacks descends along the raceway, and means for constraining the tacks to descend along the raceway with their heads in edge-to-edge relation until they reach said interrupted portions of the flat raceway surfaces.

19. In a tack-separating mechanism, an inclined raceway provided with a tack-feeding groove and adjacent flat surfaces for engaging the heads of the tacks in said groove, a separator arranged to reciprocate along the lower end face of the raceway provided with a tack-receiving recess, said raceway being inclined from the horizontal at an angle sufficient to cause tacks to slide by gravity with their heads on said flat surfaces and said flat raceway surfaces each being interrupted by an angular notch having a bottom surface of considerably less inclination than that of the raceway so as to cause the leading edge of the head of each succeeding tack to be superposed on the trailing edge of the head of the preceding tack, as a line of tacks descends along the raceway, and means for constraining the tacks to descend along the raceway with their heads in edge-to-edge relation until they reach said notches in the flat raceway surfaces.

20. In a tack-separating mechanism, an inclined raceway provided with a tack-feeding groove and adjacent flat surfaces for engaging the heads of tacks in said groove, a separator arranged to reciprocate along the lower end face of said raceway provided with a tack-receiving recess and having an upper surface inclined in the opposite direction to said raceway, said raceway being inclined from the horizontal at an angle sufficient to cause tacks to slide by gravity with their heads on said flat surfaces and their stems suspended in said groove and the flat raceway surfaces, adjacent to the upper end of the raceway, each being interrupted by an angular notch having a bottom surface of considerably less inclination than that of the raceway so as to cause the leading edge of the head of each succeeding tack to be superposed on the trailing edge of the head of the preceding tack as a line of tacks descends along the raceway, and means for constraining the tacks to descend along the raceway with their heads in edge-to-edge relation until they reach said notches in the flat raceway surfaces.
